UNITED STATES PATENT OFFICE.

WILLIAM E. CRAMER, OF COLUMBUS, OHIO, ASSIGNOR TO THE HARROP CERAMIC SERVICE COMPANY, OF COLUMBUS, OHIO, A CORPORATION OF OHIO.

METHOD AND APPARATUS FOR TREATING CLAYWARE.

Application filed December 27 1927. Serial No. 242,709.

My invention relates to method and apparatus for treating clay ware and has to do primarily with the drying and burning of such ware. It pertains particularly to a novel 5 method and apparatus for drying and the combination thereof with what is known as the continuous car tunnel kiln and associated transporting mechanism.

In the manufacture of clay ware by the 10 plastic process, the previous methods of drying the ware and getting it into and through the continuous car tunnel kiln have resulted in an unnecessary amount of handling of the ware and of delay in the whole process. The 15 usual procedure has been to dry the ware upon separate drier cars and to then take it from these drier cars and set it upon the kiln cars to full kiln-setting height. It has not been practicable to set the ware, while in plastic state 20 to the full kiln-setting height, usually ranging from 13 to 15 courses. In fact, experience has shown that plastic ware, such as brick, cannot be safely set to a greater height than 7 or 25 8 courses, on edge, without damage to the lower courses during drying. Thus, it has been customary in drying, to limit the height of setting to 7 or 8 courses on drier cars and then, after the necessary accumulation of dried 30 ware has been obtained, to set this dried ware to full kiln-setting height on kiln cars and 35 pass it through the kiln for burning. This has necessitated the use of a large number of drier cars and a large amount of extra equipment, such as trackage etc.

I have recognized the disadvantages of this 40 practice and have devised a novel process for handling the ware during the drying and burning operations, so that the number of cars and the amount of equipment necessary will be materially reduced and so that considerably less labor will be required in the course 45 of the process. In accomplishing this I have provided new apparatus and a new arrangement of the apparatus used.

My process contemplates the placing of the 50 plastic ware upon the kiln cars in the first instance, instead of first setting it upon drier cars and then after drying, resetting it upon the kiln cars. That is, I first place a setting of 55 plastic ware upon kiln cars, preferably limiting this setting to 7 or 8 courses. Then, I send the kiln cars, with this setting thereon, through a drying unit which is of appropriate cross-section to effect proper drying. When

in a dried state, I then superimpose a series of courses of undried ware upon the said dried setting and upon the same kiln car. I then pass the same kiln car with the dried and undried ware thereon through another drier 60 unit. Two or more drier units may be used successively in this way. Finally, however, the whole setting of ware which has been dried in these successive stages and which is still 65 upon the same kiln car is sent through the kiln upon this kiln car. It will be understood that the drying units are successively higher, but that the particular height of any drying unit may be altered as desired. Likewise, these drier units may be equipped with one or 70 more parallel tracks and they may be either of tunnel or other type.

One type and arrangement of apparatus which I may use, is shown in the accompanying drawings wherein similar characters of 75 reference designate corresponding parts and wherein:

Figure 1 is a perspective view of one type of apparatus used by me in the practicing of my method.

Figure 2 is a plan view of this apparatus.

Figure 3 is a side elevation taken on line 3—3 of Figure 2.

Figure 4 is a side elevation taken on line 4—4 of Figure 2.

In the drawings, it will be seen that I have provided a conveyer 1 which is designed to conduct the undried clay ware to a point adjacent the return track and near the charging end of the first drier unit. Some of the ware may be unloaded at this point either automatically or manually as desired and placed on the kiln cars to partial kiln-setting height. The conveyor 1 also conducts some of the plastic ware to a point beyond the first drier 90 unit for the second loading to be described.

The first drier unit may be designated 2. It is of any desired form, being preferably of the tunnel type as shown in the drawing. By reference to Figure 3, it will appear that the roof of this drier unit is low, being particularly so in comparison with the second drier unit 3. The drier unit 3 is of about the height of the tunnel kiln 4, being adapted to permit the passage therethrough of a kiln 105 car with a setting which is the full kiln-setting height, of approximately 13 to 15 courses of ware, while the drier unit 2 is adapted to permit the passage therethrough of a kiln car 110 with only 7 or 8 courses of ware.

The car, which is used both for drying and burning, may be generally designated 5 and may travel upon a track 6 which passes through the drier unit 2 and then through the 5 drier unit 3. These drier units are preferably in alignment to facilitate such passage. The track 6, beyond the drier unit 3, leads to a transfer track 7 disposed in a pit 8.

A transfer car 9 is mounted in the pit 8 10 and adapted to travel upon track 7. This transfer car is provided with rails 10 and can be moved into position to receive a car on such rails 10 after it leaves the drier unit 3 and can then be transferred to a point for 15 delivery of such car to the track 11.

The track 11 passes through the tunnel kiln 4 and leads to another transfer track 12 in a pit 13. A transfer car 14 substantially identical with the transfer car 9 is adapted to receive the cars with the burnt ware thereon, as they leave the tunnel kiln 4. After these 20 cars have been transferred to the car 14, they may then be delivered to any desired location for unloading and may then be moved to the desired point for resetting preparatory to passing through the first drier.

Briefly reiterating the method of use of this apparatus, it will be understood that 30 part of the ware is dried on the cars in passing through the drier 2. Additional undried ware is then superimposed on this already-dried ware and then passed with the dried ware through the drier unit 3. The ware, as it leaves the drier unit 3 constitutes a complete setting and is then transferred to the 35 track 11. Then, it is passed through the tunnel kiln 4.

It will be obvious that more than two drier 40 units may be provided in cooperation with one tunnel kiln. The number of courses of ware first set on a car may vary, this depending somewhat upon the type of ware being treated and the drying characteristics of the clay. Likewise, the number of courses superimposed upon any partial setting of ware may be 45 varied as desired. Three or four or more drier units may be used for each tunnel kiln if desired.

It will be obvious that I have provided a 50 novel process, apparatus and arrangement of apparatus which entirely eliminates the necessity of using separate drier cars without increasing the number of kiln cars necessary for burning the ware. It will also be apparent that, with my process, it is necessary to set the ware only once, each piece of ware being set in the first instance upon the kiln car, which is to finally carry it through the kiln. This greatly reduces the handling of 55 the ware and renders unnecessary the holding of a large number of cars with dried ware thereon, pending the accumulation of sufficient ware for the kiln car setting. Thus, my 60 process results in the saving of labor, time and equipment. Other advantages have

been touched upon and will appear from the appended claims.

It will, of course, be understood that, throughout this specification, I have used the terms "dried" and "undried" in a relative 70 sense only. For instance, each setting of ware upon a kiln car need be dried only sufficiently to support without damage, the additional setting of ware to be superimposed thereon.

Having thus described my invention, what 75 I claim is:

1. The method of treating clay ware which comprises setting the ware in a plastic state upon tunnel kiln cars to a partial height of the normal setting for the kiln, passing the 80 ware thus set through a drier of appropriate cross-section, superimposing additional courses of undried ware on the setting of ware thus dried, passing this setting of dried and undried ware through another drier of appropriate 85 cross-section and then passing the ware through a tunnel kiln.

2. The method of treating clay ware which comprises passing a partial setting of the 90 ware on tunnel kiln cars through drier of appropriate interior cross-section, superimposed additional courses of undried ware thereon, passing these courses of dried and undried ware through another drier of appropriate interior cross-section, and then burning the 95 complete setting.

3. The method of drying clay ware preparatory to passage through a tunnel kiln which comprises setting a portion of the ware 100 in plastic state upon a tunnel kiln car, passing this portion through a drier, setting another portion of undried ware on the said first portion which has been dried and then passing this setting of dried and undried ware through another drier.

4. The method of treating plastic clay ware which comprises placing a partial setting of undried ware on a tunnel kiln car, passing it through a drier, superimposing additional courses of undried ware on this previously 110 dried partial setting and passing the dried and undried ware through another drier.

5. A method of treating plastic clay ware which comprises placing a partial setting of undried ware on a tunnel kiln car, passing it 115 through a drier with a low roof, superimposing additional courses of undried ware on this previously dried partial setting and passing the whole through a drier with a comparatively high roof.

6. Apparatus for treating plastic clay ware comprising the combination of a plurality of drying units of successively increasing height, and trackage extending through said drying units whereby a partial setting of ware in 125 plastic state can be sent through the drying unit of lesser height, additional plastic ware set upon the ware so dried and the dried and undried ware set through the next drying unit of greater height.

7. Apparatus for treating plastic clay ware comprising the combination of a plurality of drying units of successively increasing height, a tunnel kiln, and trackage extending through said drying units and said kiln whereby a partial setting of ware in plastic state can be sent on kiln cars through the drying unit of lesser height, additional plastic ware set upon the ware so dried, the dried and undried ware sent through the next drying unit of greater height, and the whole setting then sent through the tunnel kiln for firing.

8. Apparatus for treating plastic clay ware comprising the combination of a plurality of drying units of successively increasing height and each constructed to permit the passage

therethrough of ware on tunnel kiln cars, a tunnel kiln, and trackage extending through said drying units and said kiln whereby a partial setting of ware in plastic state can be sent 20 through the drying unit of lesser height on tunnel kiln cars, additional plastic ware superimposed upon the dried ware on said cars, the dried and undried ware sent through the next drying unit of greater height, on the 25 same car, and the whole setting then sent through the tunnel kiln for firing on the same car.

In testimony whereof I hereby affix my signature.

WILLIAM E. CRAMER.

CERTIFICATE OF CORRECTION.

Patent No. 1,709,063.

Granted April 16, 1929, to

WILLIAM E. CRAMER.

It is hereby certified that error appears in the printed specification of the above numbered patent requiring correction as follows: Page 2, line 91, claim 2, for the word "superimposed" read "superimposing"; same page, line 109, claim 4, for the word "dried" read "drier", and line 113, claim 5, for "A method" read "The method"; page 2, line 129, claim 6, for the word "set" read "sent"; and that the said Letters Patent should be read with these corrections therein that the same may conform to the record of the case in the Patent Office.

Signed and sealed this 4th day of June, A. D. 1929.
